CLAIM

The ornamental design for an indoor unit for an air conditioner, as shown and described.

DESCRIPTION

The patent or application file contains at least one drawing executed in color. Copies of this patent or patent application publication with color drawing(s) will be provided by the Office upon request and payment of the necessary fee.

1. Indoor unit for an air conditioner

1.1 : Perspective

1.2 : Front

1.3 : Left

1.4 : Right

1.5 : Top

1.6 : Bottom

Fig. 1.1 to fig. 1.6 show an indoor unit for an air conditioner according to the present design.

The portions of the design shown in the color red are for the purpose of illustrating portions of the indoor unit for an air conditioner and form no part of the claimed design.

1 Claim, 6 Drawing Sheets
